UNITED STATES PATENT OFFICE.

JACOB O. CAMPBELL, OF BIG RUN, AND PAUL CAMPBELL, OF ANITA, PENNSYLVANIA.

GREASE AND OIL GUN.

1,181,837.

Specification of Letters Patent. Patented May 2, 1916.

Application filed April 2, 1915. Serial No. 18,701.

To all whom it may concern:

Be it known that we, JACOB O. CAMPBELL, a citizen of the United States, residing in Big Run, in the county of Jefferson and State of Pennsylvania, and PAUL CAMPBELL, a citizen of the United States, residing in Anita, in the county of Jefferson and State of Pennsylvania, have invented certain new and useful Improvements in Grease and Oil Guns, of which the following is a specification.

This invention relates to apparatus especially intended for installing heavy grease in mine cars, but may be employed for other purposes, and the object of our invention is to provide an apparatus of this kind in which the grease may be readily and positively withdrawn from a reservoir and positively discharged through a nozzle or other such device.

In carrying out our invention we provide a pump, comprising a pump barrel having a tapered delivery end to which the nozzle is applied, and within the barrel we mount a rod carrying two pistons of different diameters, one of which fits closely the body or outer part of the barrel and the other of which is adapted to fit closely a portion of the tapered part of the barrel. A check valve or, as we call it vacuum valve, is mounted between the nozzle and the pistons and is adapted to open during delivery and to close during the backward movement of the pistons. A reservoir containing the grease is connected with the barrel and a valve is mounted in this connection which opens during the backward movement of the pistons but closes when the pistons move forwardly toward the delivery end of the pump.

In the accompanying drawings:—Figure 1 shows a vertical longitudinal section through a grease or oil gun embodying our improvements some parts, however, being shown in elevation. Fig. 2 is a perspective view of the valve box interposed between the reservoir and the pump barrel. Fig. 3 is a perspective view of the valve operating in said valve box. Fig. 4 is a detail view, mainly in section and on an enlarged scale, showing the larger of the two pistons and indicating how it is connected with the piston rods. Fig. 5 is a similar view of the smaller piston.

The pump barrel A is provided at one end with a cap a and at its opposite end it

has a tapered front portion a' which is preferably made separately and attached to the body of the barrel by a suitable joint a². A nozzle B is attached to the outer end of 60 the tapered portion a' and may be of any suitable kind. Within the tapered portion a' of the pump barrel is a check valve or vacuum valve C and this is preferably carried by a frustum-shaped frame c mounted 65 in and fixed to the tapered part a'.

The reservoir D is preferably of the kind shown and connects with the pump barrel through a valve box E which is firmly attached to the reservoir and to the pump 70 barrel and has a wide opening e through which the grease or heavy oil passes from the reservoir, and it has another opening e' which establishes communication between the valve box and the pump barrel. The 75 valve F comprises a part f adapted to close the opening e and slotted wings f' through which extends the supporting and guiding rod G. The valve is free to move toward and from the opening e during the operation 80 of the pump. The piston rod H is provided with a handle h and extends through the cap a into the barrel. It carries a piston P adapted to reciprocate in the body of the barrel, and it is connected by means of a 85 rod h' with another piston P' of smaller diameter and adapted to enter the tapered portion a' of the barrel. Preferably the pistons are of the kind shown in Figs. 4 and 5. The piston P comprises a disk p provided with a thimble p' which receives the inner end of the rod H'. p² indicates a 90 leather or other suitable flexible covering for the piston which is held in place by a washer p³. The piston P' comprises a disk q attached to the end of the rod h' and a covering q' of flexible material held in place by a washer q².

Fig. 1 shows the apparatus in the condition it assumes when the pistons have been 100 forced inward to their full extent. At this time the valve F is opened. If, now, the pistons are moved rearward the check valve or vacuum valve C will close, and a vacuum or partial vacuum will form between the 105 pistons and said vacuum valve. The grease or oil will flow past the valve F into the pump barrel, enter the space between the two pistons and also pass into the tapered portion of the pump barrel in rear of the 110 valve C. When the pistons have been drawn rearward to the desired extent, their move-

- ment is reversed. When this occurs the valve F is closed and the grease in front of the piston P' is forced past the valve C into the front part X of the barrel and thence 5 outward through the nozzle B. At the same time the grease between the pistons P, P' is moved forward by the piston P. When the pistons are moved rearward again the valve C quickly closes, leaving some grease in the 10 chamber X and during this rearward movement grease passes to the front or inner side of the piston P' and is afterward forced into the chamber X on the return movement of the pistons.
- 15 By this apparatus grease or heavy oil may be transferred from a reservoir to any suitable object or receptacle.
- We claim as our invention:
1. A grease gun, comprising a pump barrel having portions of different diameters the smaller of which is provided with a discharge opening, a reservoir connected with that portion of the barrel having the larger diameter, a valve interposed between the 20 pump barrel and the reservoir for limiting the passage of grease from the reservoir to the barrel, a check valve in the smaller portion of the barrel located between the discharge opening thereof and the communication 25 between the barrel and the reservoir, a piston rod and pistons thereon of different diameters one of which reciprocates only in that portion of the barrel having the larger diameter and the other of which reciprocates 30 in rear of the check valve in both the larger and smaller portions of the barrel whereby grease may flow past the smaller piston toward the discharge opening and into the 35 smaller portion of the barrel between the smaller piston and the check valve.
  - 40 2. A grease gun, comprising a pump barrel having a tapered portion at one end, a reservoir communicating with the barrel, a valve interposed between the reservoir and

the pump barrel, a piston rod operating in 45 the barrel and having a piston making close contact with the barrel, and another piston of smaller diameter adapted to make close contact with the tapered portion of the barrel, a nozzle for the barrel, and a valve interposed between the nozzle and the outer 50 end of the piston rod.

3. A grease gun, comprising a pump barrel having a tapered portion at one end, a check valve mounted in the tapered portion 55 of the barrel, a reservoir communicating with the barrel, a valve interposed between the reservoir and the barrel, a piston rod, a piston reciprocating therewith, and another piston of smaller diameter separated 60 from the piston first-mentioned and adapted to make close contact with the tapered portion of the barrel.

4. A grease gun, comprising a pump barrel having portions of different diameters 65 the smaller of which is provided with a discharge opening, a reservoir connected with that portion of the barrel having the larger diameter, a valve interposed between the pump barrel and the reservoir, a check valve 70 interposed between the discharge opening and the communication between the reservoir and the pump barrel, a piston rod, a piston thereon reciprocating in the larger portion of the barrel only, and another piston 75 on said rod separated by a space from the first-mentioned piston and which reciprocates in both the larger and smaller portions of the barrel between the check valve and the communication between the 80 reservoir and the barrel.

In testimony whereof, we have hereunto subscribed our names.

JACOB O. CAMPBELL.
PAUL CAMPBELL.
